UNITED STATES PATENT OFFICE.

ELBRIDGE S. BICKFORD, OF BRISTOL, NEW HAMPSHIRE.

SPRINKLING DEVICE.

1,039,084.

Specification of Letters Patent. Patented Sept. 24, 1912.

Application filed November 29, 1911. Serial No. 663,140.

To all whom it may concern:

Be it known that I, ELBRIDGE S. BICKFORD, a citizen of the United States, residing at Bristol, in the county of Grafton and State of New Hampshire, have invented certain new and useful Improvements in Sprinkling Devices; and I do hereby declare the following to be a full, clear, and exact description of the invention, such as will enable others skilled in the art to which it appertains to make and use the same.

My invention relates to new and useful improvements in sprinkling devices and more particularly to a device of the class described, adapted to be used in extinguishing fires.

The object of my invention is to provide a device which may be positioned in the upper part of a room and which is normally out of operation and which will be automatically opened in case of fire.

A further object of my invention is to so construct the nozzle that the fluid directed therethrough will be given a rotary movement, causing the same to spread.

Other objects and advantages will be hereinafter set forth in the specification and pointed out in the claim.

In the accompanying drawings I have shown the preferred form which my invention may take.

In said drawings, Figure 1 is a longitudinal sectional view through the nozzle. Fig. 2 is a horizontal sectional view therethrough, as seen on line 2—2, Fig. 1, and, Fig. 3 is a vertical sectional view therethrough as seen on line 3—3, Fig. 1.

Referring to the drawings in which similar reference numerals designate corresponding parts throughout the several views, 4 is a casing, which is separated into an upper and lower compartment by means of a partition 5. The upper portion of the casing is substantially cylindrical and is directed rearwardly and externally screw threaded, as shown at 6, so that a suitable supply pipe for water or other fluid may be connected thereto.

The lower compartment is substantially semispherical, as shown in Fig. 2, said semispherical portion being directed downwardly and provided at its center with an outlet opening 7, through which the fire extinguishing fluid is adapted to be directed. The partition 5 is provided at diametrically

opposite points with openings 8 therein, said openings being inclined in opposite directions so that the fluid passing therethrough into the lower compartment will be given a rotary movement therein, as will be clearly apparent to those skilled in the art to which this invention appertains. The walls of the upper compartment are also inclined, as shown at 9 and 10, over the openings 8 to assist in giving the extinguishing fluid a rotary movement in the lower compartment.

In order that the outlet opening 7 may be normally closed, I provide a valve 11, which is adapted to be normally held in said opening. The valve 11 is preferably provided with an annular flange 12, adapted to engage the outer surface of the casing, a suitable washer 13 being interposed between said flange and said casing so as to prevent leakage. The casing is provided with diametrically opposed downwardly directed stems 14 and 15, the lower end of the stem 15 being preferably screw threaded. A bar 16 having a bifurcated end, is pivoted to the stem 14, as shown at 17, the opposite end of said bar being provided with an aperture 18 therein adapted to receive the threaded end of the stem 15. The bar 16 is also provided at its center with an interiorly screw threaded aperture 19, adapted to receive a bolt 20 therethrough. The inner end of the bolt 20 may be enlarged, as shown at 21, and is adapted to be turned against the outer end of the valve 11. A nut 22, formed of easily fusible metal, is turned upon the outer end of the screw threaded stem 15, so as to hold the bar 16 in position, as shown in Fig. 3. The bolt 20 is then turned so as to tightly seat the valve 11 in the opening in the casing. A spring 23 has one end seated in a recess 24 formed in the casing, its other end bearing against the bar 16 and tends to move the bar away from the stem 15.

In operation the nozzle is positioned in a room near the ceiling thereof and is connected to a supply pipe for water or other desired fire extinguishing fluid. Should a fire occur in the room, the heat thereof will quickly melt the fusible nut 22 and the spring 23 will move the bar so that the bolt 20 will be moved out of the path of the valve 11. The pressure of the water or other fire extinguishing fluid will immediately unseat the valve, and owing to the fact

that the water will be given a rotary movement in the lower portion of the casing, the same will be sprayed and directed into all parts of the room, so that the fire will be quickly extinguished.

While I have shown and described my invention as being disposed so that the discharge or outlet opening is downwardly directed, I desire it to be understood that I may direct the same upwardly or in any other direction, so that upon the occurrence of a fire in a predetermined location, the fire extinguishing fluid will be most advantageously directed upon the flames.

From the foregoing description it will be seen that I have provided a fire extinguishing device, which is normally inoperative and which will quickly be brought into operation on the occurrence of a fire. It will also be seen that owing to the construction of my device, the fire extinguishing fluid will be directed over a large surface.

While I have shown the preferred form which my invention may take, I desire it to be understood that certain modifications

may be made therein without departing from the spirit and scope of my invention.

What I claim as new is:

The combination with a rotary sprinkler having inlet and outlet openings therein; of a pair of integral stems depending from said casing, the lower end of one of said stems being reduced and threaded, a bar pivoted to the other stem, means carried thereby for closing said outlet opening, a fusible nut threaded on the reduced end of said stem and engaging the free end of said bar, and a spring carried by said sprinkler and engaged against the upper face of said bar whereby when the free end of the latter is released it will be thrown into a vertical position and out of the path of the fluid issuing from the outlet opening.

In testimony whereof I have signed my name to this specification in the presence of two subscribing witnesses.

ELBRIDGE S. BICKFORD.
